(57) CLAIM

The ornamental design for an food holder as shown.

DESCRIPTION

FIG. 1 is a perspective view of a food holder showing my new design in an open state; FIG. 2 is a top plan view thereof; FIG. 3 is a bottom plan view thereof; FIG. 4 is a left side view thereof; and, FIG. 5 is a right side view thereof.

The broken dash-dash lines shown in FIGS. 1-5 are for illustrative purposes only and form no part of the claimed design. The dot-dash lines shown in FIGS. 1-5 are included to represent fold lines and form no part of the claimed design.

1 Claim, 5 Drawing Sheets(56)
